Assignors to

Grefoon, Stuart, & Peterson, of Philadelphia, Pa.

Letters Patent, No. 841, dated October 7, 1856.

The Schedule referred to in these Letters Patent and making part of the same.

To all to whom these presents shall come,

Be it known that we, Jacob Beesley, and Edward J. Delany, of Philadelphia, and State of Pennsylvania, have invented a new design for a stove, and that the following is a full, clear, and exact description of the principle or character which distinguishes it from all other things before known, and of the usual manner of making, modifying and using the same, reference being had to the accompanying drawings.

Fig. 1, is a view of the front and doors.

Fig. 2, is a view of the top plate.

Fig. 3, is a view of the scroll for front of stone.

These drawings illustrate our design for the parlor stone, other parts of the stone being plain and ornamental at pleasure.

What we claim as our invention, is the design for Parlor Stone as herein above illustrated and set forth.
